UNITED STATES PATENT OFFICE.

ELEANOR A. BUFF, OF HAWKINSVILLE, GEORGIA.

TATTING-NEEDLE.

1,116,792.

Specification of Letters Patent. Patented Nov. 10, 1914.

Application filed April 15, 1914. Serial No. 832,036.

To all whom it may concern:

Be it known that I, ELEANOR A. BUFF, a citizen of the United States, residing at Hawkinsville, in the county of Pulaski and 5 State of Georgia, have invented a new and useful Tatting-Needle, of which the following is a specification.

The device forming the subject matter of 10 this application is a tatting needle, and one object of the present invention is to provide a device of this sort which may be fashioned at trifling expense out of a single piece of material.

Another object of the invention is to provide 15 a tatting needle which will hold the cord which is assembled with the needle firmly but yieldably without causing a distortion or bending of the needle.

It is within the scope of the invention 20 to improve generally and to enhance the utility of, devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the accompanying drawing:—Figure 1 shows in plan, one form of needle embodying 35 the present invention; Fig. 2 is an elevation of the needle shown in Fig. 1; Fig. 3 is a plan showing a modified form of needle; Fig. 4 is a plan showing the cord assembled with that form of needle which 40 is depicted in Fig. 1.

The tatting needle herein disclosed preferably is fashioned from a single piece of material, of resilient qualities, blued steel being preferred. The needle includes a body 45 portion 1, the body portion 1 being bent at both ends as indicated at 2 to form U-shaped heads 3, one side portion 4 of each head 3 being prolonged and bent upon itself as shown at 5 to form a prong 6, the free end 50 7 of which is disposed adjacent the free end 8 of the head 3. As depicted in Fig. 1, the

free end 7 of the prong protrudes slightly beyond the free end 8 of the head 3 at both ends of the needle.

In Fig. 3, a modified form of the invention is delineated and parts hereinbefore described are referred to by the reference characters previously used, with the suffix "a." The only difference between the needle shown in Fig. 3 and the needle shown in Fig. 1 is that one of the free ends 7^a of the prongs 6^a terminates adjacent the corresponding free end 8^a of the head 3^a, instead of extending beyond the free end 8^a of the head.

The parts 4, 5 and 6 define a resilient cord holding loop terminating in a free prong 7. The cord, indicated by the reference character 9 is engaged with these loops and yieldingly held thereby, the loops being 65 resilient. It is to be observed that the heads 3 lie upon opposite sides of the body 1, the prongs 6 lying upon opposite sides of the body. In other words, the heads 3 are diagonally disposed with respect to each other 70 and a corresponding relation exists between the prongs 3. Owing to this construction, the needle is reinforced, and the tendency for the needle to swing or bend laterally when the cord 9 is assembled with the 75 resilient loops is correspondingly diminished.

The word "cord" is to be construed as meaning any material which may be handled expeditiously in a device of this type.

Having thus described the invention, what 85 is claimed is:

1. A tatting needle provided at its ends with resilient cord holding loops terminating in free prongs, each prong defining one side of the loop and each prong being extended beyond the other side of the corresponding loop.

2. A tatting needle fashioned from a single piece of material bent at one end to form a U-shaped head, one side portion of the 95 head being prolonged and bent upon itself to form a prong, the free end of which is disposed adjacent the free end of the head.

3. A tatting needle fashioned from a single piece of material and including a body, the body being bent at both ends to form U-shaped heads, one side portion of each

head being prolonged and bent upon itself to form a prong, the free end of which is disposed adjacent the free end of the corresponding head, the heads lying upon opposite sides of the body and the prongs lying upon opposite sides of the body.

In testimony that I claim the foregoing

as my own, I have hereto affixed my signature in the presence of two witnesses.

ELEANOR A. BUFF.
